DESIGN FOR AN ELECTRIC DRIER CASING

Elmer S. Hewitt, Wilmette, Ill., assignor to Electric-Aire Engineering Corporation, Chicago, Ill., a corporation of Illinois

Application January 14, 1948, Serial No. 143,744

Term of patent 7 years

(Cl. D4—3)

To all whom it may concern:

Be it known that I, Elmer S. Hewitt, a citizen of the United States, residing at Wilmette, in the county of Cook and State of Illinois, have invented a new, original, and ornamental Design for an Electric Drier Casing, of which the following is a specification, reference being had to the accompanying drawing, forming part thereof, wherein—

Figure 1 is a front elevational view of an electric drier casing, showing my new design;

Fig. 2 is a side elevation thereof; and

Fig. 3 is a top plan view thereof.

I claim:

The ornamental design for an electric drier casing, as shown.

ELMER S. HEWITT.
